(57) **CLAIM**

The ornamental design for a dry erase board, as shown and described.

DESCRIPTION

FIG. 1 is a perspective view showing our design for a dry erase board;

FIG. 2 is a top plan view of the dry erase board of FIG. 1; FIG. 3 is a front view of the dry erase board of FIG. 1; FIG. 4 is a bottom plan view of the dry erase board of FIG. 1;

FIG. 5 is a perspective view showing a second embodiment of our design for a dry erase board;

FIG. 6 is a top plan view of the dry erase board of FIG. 5; FIG. 7 is a front view of the dry erase board of FIG. 5; and, FIG. 8 is a bottom plan view of the dry erase board of FIG. 5.

The dashed lines are for illustrative purposes only and form no part of the claimed design.
